John D. Beinert, Babylon, N.Y., assignor to International Patent Research Corp., New York, N.Y., a corporation of New York

Filed Nov. 15, 1966, Ser. No. 4,678

Term of patent 7 years

(Cl. D91—1)

FIG. 2

FIG. 3

FIG. 5

FIG. 6

FIG. 1 is a perspective view of a traveling lawn sprinkler showing my new design;

FIG. 2 is a top plan view thereof;

FIG. 3 is an elevational view taken from the side opposite that shown in FIG. 1;

FIG. 4 is a rear elevational view thereof;

FIG. 5 is a front elevational view thereof, and;

FIG. 6 is an elevational view taken from the side shown in FIG. 1.

The dominant portions of the design are those shown in solid lines, it being understood that the fragmentary broken line representation of a hose in FIG. 1 is for purposes of illustration only.

I claim:

The design for a traveling lawn sprinkler, as shown and described.
